UNITED STATES PATENT OFFICE.

THOMAS E. MURRAY, OF BROOKLYN, NEW YORK.

HEAT-CONDUCTING TUBE.

Application filed June 20, 1924. Serial No. 721,180.

In certain prior applications, Nos. 642,427 filed May 31, 1923, and 642,725 filed June 1, 1923, I have described a certain hollow construction for walls and other parts of boilers or heaters and made up of tubes of rectangular, circular or irregular cross-section with fins or flanges extending lengthwise thereof so as to provide a heating surface exposed to the heating gases greater than the surface which is in contact with the water or other fluid in the tube.

The present invention provides a unit from which such boiler walls and the like may be built. The accompanying drawings illustrate embodiments of the invention.

Fig. 1 is a horizontal section of a side wall of a boiler built with the tubular units of the invention;

Fig. 2 is a perspective view partly in section showing the ends of certain oblong tubes and their connection with a header;

Figs. 3 to 8 are plans of various forms of unit made in accordance with the invention.

Referring to Fig. 1, the boiler wall is made with an inner lining or screen comprising tubes 1 with lateral fins or extensions across the spaces between the tubes. On the outside of this screen is the wall of the boiler structure which may be of any usual or suitable material and which as illustrated comprises refractory blocks or bricks 3 outside of which are tiles 4 of non-conducting material and an outer shell 5 of sheet metal. The longitudinal fins extend throughout such portions of the length of the tube as may be desired according to the design of the boiler and throughout the zone where their conducting effect is desirable. As shown in Fig. 2, they extend to a header 6 into which the upper ends of the tubes are introduced.

The lateral extensions on the tubes may be of various shapes. They are preferably in the form of two plates alongside of each other, either in contact or spaced apart. For example, in Fig. 2, we have the circular tubes 1 and between them we have extensions comprising flattened tubes with two parallel walls 7 spaced apart from each other and with convex ends which are welded to the circular tubes at 8. Fig. 3 illustrates a structure in which a number of circular tubes and flat tubes are welded edge to edge in a single structure. Instead of this, the

wall may be made in units which are separate from each other, each unit comprising a circular tube with an extension at one side; or a tube having extensions welded to both sides of it and the next circular tube being plain.

According to Fig. 4, the extension comprises a rolled shape having two opposite diverging sides 9 welded at their ends to the circular tube as at 8 and connected at their outer edges by a portion 10.

According to Fig. 5, a known rolled shape comprising two diverging members 11 is welded at the inner edges thereof, these members being connected at their outer edges to a broad flange 12.

According to Fig. 6, the tube 1 has welded directly to it at 8 a plate 13 with a flange 14 at its outer edge, and a separate plate 15 is set in the space between the flange 14 and the tube. This sort of double extension may be provided at each side of the tube as shown at the left and a similar extension may be provided at the inner face of the tube, that is, the face exposed to the fire, as for the right hand tube.

According to Fig. 7, the extension comprises a looped sheet 16, the inner edges of which are brought together and welded to the tube as at 8.

According to Fig. 8, a similar construction is obtained by uniting two segments each having a semi-circular central portion 17 with flat side portions 18 on the ends of which are flanges 19, which flanges are welded together along joints 20. Since this flanged tube, thus constructed, is exposed to the pressure within the tube, it is advisable to fasten the flanges 18 together, and this is accomplished by spot-welding or otherwise welding them at 21.

In all the above cases, it will be observed that the lateral extensions from the tubes are of double thickness, so that only one face of the metal is exposed to the destructive effect of the fire. The inner faces of the looped constructions of Figs. 4 and 5, for example, are protected from direct exposure to the flames. The principal purpose of such construction is to increase the durability of the fins or extensions.

Incidentally such extensions may be made to serve also as tubes for carrying water or fluid to be heated. And such an arrangement is shown in Figs. 1, 2 and 3. Or the

main tubes 1 may carry the water and the lateral tubular extensions 7 may carry air or other fluid to be heated. Where flat tubes are used to carry the water, the upper ends thereof should be reduced to a circular shape as shown, for example, at 22 in Fig. 2. Generally the wall made up of these units is not a closed, gas-tight structure but admits the flame to some extent to the back as well as to the front of the lateral extensions provided. Therefore, by protecting one face of the metal, their durability is increased. This is particularly true where one of the extensions projects directly into the furnace as in the case of the unit at the right of Fig. 6. Although I have referred to each unit as consisting of a single tube with an extension at each side of it, yet it may consist of a plurality of tubes with proper extensions. For example, Fig. 3 may be taken to illustrate a unit consisting of two tubes 1 with a connecting hollow web; a number of such units being used separately to build up a wall with contacting or overlapping edges. A full description of the method of use of these units and of the best methods of welding the parts together is described in another application which I have filed concurrently herewith, Serial No. 715,369 filed May 23, 1924. As described in said application also, the lateral extensions applied to the tubes can advantageously be made of special metal or specially coated to resist deterioration by the heat. But this is not so important in the present case where only one face of the metal is exposed to the heat.

Though I have described with great particularity of detail certain embodiments of my invention, yet it is not to be understood therefrom that the invention is restricted to the particular embodiments disclosed. Various modifications may be made by those skilled in the art without departure from

the invention as defined in the following 45 claims.

What I claim is:—

1. A heat conducting unit for boilers comprising a tube for water with an external lateral extension lying substantially parallel 50 to the tube and exposed to the heating gases, said extension being composed of two parts, one of which lies in front of the other and shields a face of it from the heating gases. 55

2. A heat conducting unit for boilers comprising a tube for water with an external hollow lateral extension lying substantially parallel to the tube and exposed to the heating gases. 60

3. A heat conducting unit for boilers comprising a tube for water with an external lateral extension lying substantially parallel to the tube and exposed to the heating gases, said extension being composed of two parts 65 welded to the tube and one lying in front of the other.

4. A heat conducting unit for boilers comprising a tube for water with an external hollow lateral extension welded to said tube 70 and lying substantially parallel thereto and exposed to the heating gases.

5. A heat conducting unit for boilers comprising a tube for water with an external lateral extension consisting of a second tube 75 welded to the first and lying substantially parallel thereto and exposed to the heating gases.

6. A heat conducting unit for boilers comprising a tube for water with an external 80 lateral extension consisting of a second tube flattened and welded at an end of its longer diameter to the first tube and lying substantially parallel thereto and exposed to the heating gases. 85

In witness whereof, I have hereunto signed my name,

THOMAS E. MURRAY.
